RAZOR-BLADE SCRAPER

Thomas F. Howerter, Fort Collins, Colo., assignor to
Carol Company, Fort Collins, Colo.

Filed Aug. 25, 1969, Ser. No. 18,883

Term of patent 14 years

Int. Cl. D7—06, 99

U.S. Cl. D49—26

FIG. 1

FIG. 2

FIG. 3

FIG. 1 is a top plan view of a razor-blade scraper embodying my new design;

FIG. 2 is a side-elevational view of the scraper shown in FIG. 1; and

FIG. 3 is a bottom view of the same scraper.

I claim:

The ornamental design for a razor-blade scraper, as shown and described.
